UNITED STATES PATENT OFFICE.

WILLIAM J. MILLER, OF COLUMBUS, OHIO.

GLASS-SHEARING DEVICE.

1,176,392.

Specification of Letters Patent. Patented Mar. 21, 1916.

Application filed August 10, 1910. Serial No. 576,531.

To all whom it may concern:

Be it known that I, WILLIAM J. MILLER, a citizen of the United States, residing at Columbus, in the county of Franklin and State of Ohio, have invented a certain new and useful Improvement in Glass-Shearing Devices, of which the following is a specification.

The object of this invention is to provide improved, simplified and effective means for use in connection with glass molding machines for severing the string of a lump of hot glass when the lump has been deposited by a punty into the mold.

The invention is embodied in the construction herein shown, described, and claimed, the invention not being confined to the particular instance of it illustrated in the accompanying drawings.

In said drawings—Figure 1 is a plan view. Fig. 2 is a vertical section on the line *x*—*x* Fig. 1. Fig. 3 is a transverse vertical section on the line *y*—*y* Fig. 2. Fig. 4 is a similar section on the line *z*—*z* Fig. 2. Fig. 5 is a side elevation. Fig. 6 is a transverse vertical section on the line *w*—*w* Fig. 5 looking to the right. Fig. 7 is a similar section on the same line *w*—*w* Fig. 5, looking to the left.

The frame upon which the shearing blades are supported or are operated comprises a portion including a cylinder 15 and a portion 16 secured to the cylinder and forming the outer head thereof. Within the cylinder is a piston 17 having its rod 18 extended through a stuffing box in the outer head of the cylinder. On the outer end of the piston rod is secured a cross head of metal 19 constituting the stock for receiving the shearing blade 20. This blade 20 has a concavely curved shearing edge as shown and is secured to the lower side of the cross head by means of a clip or plate 21 engaged by headed screws 22, 22, passed through the cross head. Threading into the cross head between the screws 22, 22, is a screw 23 the lower end of which is butted against the upper side of the blade at a middle line thereof. By turning down the screw 23 to the extent desired and tightening up the screws 22, 22, to draw up the clip and sides of the blade the shearing edge thereof can be flexed to the extent desired with a downward curve from the sides toward the middle. At the flanks of the

cross head are forwardly projecting spring presser members 24, 24, the function of which will presently appear. These spring members 24, 24, are secured by means of set screws 25, 25, threaded through the flanks 60 of the cross head and through holes in the spring members and pinching against the side portions of the clip 21. The screws 25 are held in their set position by lock nuts 26. The spring members 24, 24, are of course, 65 clamped and held from vertical movement between the cross head and clip 21 when the latter is drawn up to flex the blade, and the screw 25, because it passes through a hole in the rear end of the blade, aids in 70 securing it from longitudinal movement.

27 designates the stationary shearing blade. This blade also has a concavely curved shearing edge the curve thereof being the contrary of that of its movable companion and said blade is secured upon the forward portion 16 of the frame by means of a clip or plate 28 held upon the blade with screws 29, 29, tapping into the frame. Extending upward from the lower side of 75 the frame and between the screws 29, 29, is a screw 30 having its upper end butting against the under side of said blade at the middle line of the latter. By turning up the screw 30 to the extent desired and tightening down the screws 29, the shearing edge of the blade 27 can be flexed to the extent desired. The clips or plates 21 and 28 while thicker than the blades are sufficiently thin to be flexible when subjected at their ends 80 to the pressure of the screws and their flexion is imparted to the blades. The flexion of the plates and blades is so slight that it cannot be exactly shown in drawings upon the scale necessary herein. The under 85 sides of the ends of the plate 28 are cut away and the forward ends of the spring presser members 24, 24, are beveled as seen at 24^a, so that when the cross head carrying the movable blade is thrust outward the presser members are guided under the ends of the plate 28 and the edge of the movable blade insured contact with or at least shearing proximity to the edge of the fixed blade at 90 two points. When the two blades first contact a lenticular opening between them is formed, said opening decreasing in its major and minor axes as the movable blade advances over the fixed one. Because the shearing contacts of the blades approach 95 100

each other through the glass the latter is compressed and sheared equally at both sides toward a middle point where the final severance of the string takes place. The frame 5 below this point of the shearing operation is provided with a downwardly tapering or funnel shaped opening through which the glass is deposited by the punty to the mold.

Where my shearing device is to be used in 10 connection with a glass molding machine like that illustrated in the United States patent to Edward Miller, No. 787,050 dated April 11, 1905, it is secured to the column or post 1 of such machine and substantially 15 in the same manner as shown in my United States Patent No. 937,626 dated October 19, 1909.

The piston can be reciprocated by fluid pressure to operate the cross head and movable blade in the usual manner and substantially as indicated in my aforesaid patent. It is advantageous and preferred that the system of valves of my said patent be used especially where the invention is applied to 25 such machine. The movable blade passes above and hard against the stationary blade, their edges being forced together by the spring pressure members bearing upward against the ends of the clip of the stationary blade. Before the fluid pressure is admitted to force outward the cross head the gatherer drops a lump of glass through the funnel shaped opening described and the string of glass between the punty and the 30 lump in the mold below is sheared and severed by depressing the necessary valve to move the piston. To open the shears the pressure is, of course, admitted to the cylinder at the opposite side of the piston when 35 the operation of shearing can be repeated.

It will be observed that with this construction the use of links and other expensive or troublesome parts and connections therefor are avoided. By adjusting the 45 screws 23 and 30 or either of them the shearing blades can be flexed to secure that relative position of them necessary to effect a clean cut. Because the screws 25 are in rear of the screws 22, the knife, and the springs 50 can be given a slight adjustment with reference to the cross-head upward or downward

by properly turning down or up the screws 25.

Portions of this invention can obviously be used in combination with parts of different construction from those shown and particularly described.

What I claim is:

1. Means for shearing glass including, in combination, two blades having oppositely concavedly curved coöperating flexible shearing edges facing each other and adjustable means for flexing said edges longitudinally with reference to each other. 60

2. Means for shearing glass including, in combination, two blades having oppositely concavedly curved shearing edges, and adjustable means for flexing at least one of said blades longitudinally with reference to its shearing edge. 65

3. Means for shearing glass including, in combination, two blades at least one of which has a concavedly curved shearing edge and adjustable means for flexing each of said blades. 70

4. Means for shearing glass including, in combination, two blades at least one of which has a concavedly curved shearing edge and adjustable means for flexing at least one of said blades. 75

5. Means for shearing glass comprising, in combination, a pair of blades, one of which moves to coöperate with the other, a pair of spring members flanking one of said blades and a pair of coöperating contacts 85 for said spring members flanking the other blade, said spring members and contacts adapted to guide and hold said blades in shearing relation to each other.

6. In means for shearing glass, in combination, a support, a blade having a concavedly curved shearing edge on said support, a clip on one face of the blade with screws to secure the blade to the support, a set screw in the support between the first mentioned screws to bear upon the face of the blade opposite that engaged by said clip to flex the blade and its shearing edge. 90

95 WILLIAM J. MILLER.
